United States Patent Office.

J. TOBIAS BRAUN, OF RANDOLPH CENTRE, WISCONSIN.

Letters Patent No. 78,921, dated June 16, 1868.

IMPROVEMENT IN WIND-WHEELS.

The Schedule referred to in these Letters Patent and making part of the same.

TO ALL WHOM IT MAY CONCERN:

Be it known that I, J. TOBIAS BRAUN, of Randolph Centre, in the county of Columbia, and State of Wisconsin, have invented a new and improved Windmill; and I do hereby declare that the following is a full, clear, and exact description thereof, which will enable others skilled in the art to make and use the same, reference being had to the accompanying plate of drawings, and to the letters of reference marked thereon, forming part of this specification.

Figure 1 represents a sectional elevation of my invention.

Figure 2 is a plan or top view of the same.

Figure 3 is a detail side view of the brake-attachment.

Figure 4 is a detail sectional view, to be hereinafter referred to.

Similar letters of reference indicate corresponding parts.

This invention relates to a new self-acting windmill, which is so arranged that the horizontal axle on which the wings or sails are mounted has bearings on both ends, thereby allowing the use of less clumsy apparatus, and doing away with much friction.

The invention consists chiefly in the device for transferring motion from the horizontal wing-shaft to the horizontal driving-shaft, by which the machine to be operated is set in motion. The said device is so arranged that the horizontal wing-axle can turn freely around its own axis when revolved by the wind, and also around an imaginary vertical axis when set by the wind.

A represents the framework of a building upon which my improved windmill is to be arranged.

B is a horizontal axle, having its bearings within the building, and carrying the driving-pulley *a*, as shown. This axle is to receive motion from the windmill arranged on top of the building, and is for that purpose provided with two cranks, *b* and *c*, which are set at an angle of less than one hundred and eighty degrees, and more than ninety degrees from each other. As each of these cranks is connected with the driving-spindle, the dead-point will be overcome, and consequent stoppage of the machine will be avoided.

C is a stationary vertical tube, fitted through the roof of the building, above the crank of the axle B, in such a manner as to project above the roof D, as is clearly shown in fig. 1. A ring or stationary sleeve, *d*, is secured around this tube C, above the roof, as shown, and serves as a bearing for an upright frame, E.

The frame E consists of two or more vertical posts, *e e*, connected in a suitable manner at their upper ends, and set far enough apart to rest with their lower ends upon the ring *d*, and to fit around the tube C, as shown in fig. 1.

The frame E thus rests upon the ring *d*, and can be turned around the tube C, the axis of which is its centre of rotation.

In two opposite posts, *e*, of the frame E, are the bearings for a horizontal axle, F, said bearings being above the upper end of the tube C, as shown.

One end of the shaft F extends beyond the frame E, and carries a roller, *f*, which rests upon an annular rail, G, secured above the roof D, concentrically around the tube C, as is clearly shown in fig. 2.

The shaft F is the windmill-spindle, and carries the wings or sails H H, as shown.

It will be seen that by extending the spindle F, and supporting its outer end by means of the rail G and roller *f*, its bearing on the frame E, and the supports of the frame E, need not be nearly as strong and heavy as they would be if the spindle were only supported at one end.

As the spindle F is revolved by the wind, it is necessary to connect it with the axle B in such a manner that the rotary motion of the spindle around the axis of the tube C will not influence or strain connections, nor retard the motion of the axle.

The spindle F is between the posts *e e*, provided with three cranks, *h*, *h*, and *i*. The crank *i* is vertically above the centre of the tube C, and above the crank *e* of the axle B, while the cranks *h h* are at the sides of the crank *i*. The cranks *h h* are arranged in line with each other, and are set at the same angle with the crank

i as the cranks *b* and *c* are set with each other. The cranks *i* and *c* are connected by a rod, *I*, which is jointed at three places.

The middle joint, *j*, is a swivel, to allow the upper part of the rod to turn round its own axis when the spindle is set. The other joints, *k k*, are to allow for the inclined positions of the ends of the rod during the revolutions of the cranks.

The connecting-rod *I*, when arranged as described, might perhaps be sufficient to transfer the motion from the spindle to the axle *B*, but to overcome the dead-point it is advisable to provide another connection between the spindle *F* and the axle *B*, and immediately between the cranks *h*, *h*, and *g*. For this purpose the lower end of a rod, *J*, is secured to the crank *b*, the rod extending to the upper end of the tube *C*, and having a joint, *l*, to allow the lower part of the rod to be moved by the crank. The upper end of the rod *J* is bifurcated, and carries an annular plate, *m*, secured to the two upper ends of the rod, as shown more particularly in fig. 4, which is a detail sectional view of the upper part of the tube *C*.

To each crank, *h*, is secured a rod, *J'*, the lower ends of both these rods being pivoted to pins *n n*, which are fitted through a circular plate, *o*, and which are headed, so as to support the plate *o*, as is clearly shown in fig. 1. The diameter of the plate *o* is larger than the inner diameter of the annular plate *m*, and therefore, as the plate *o* is arranged under the plate *m*, the latter and its appendage *J* are supported by the plate *o*. Thus the rods *J* and *J'* are connected, and serve to transfer motion from the spindle *F* to the axle *B*. The rod *I* passes through a hole in the centre of the plate *o*, as shown. The plate *o* can turn freely under the wing *m*, and thus a swivel is arranged in the rod *J J'*, which allows the setting of the spindle.

The motion of the axle *B* may be retarded by means of a brake, *L*, which consists of a lever, *p*, pivoted to the framework of the building, of a connecting rod, *r*, and of a lever, *S*, as is clearly shown in fig. 3 of the drawing. By depressing the end of the lever *S*, the drum or axle *B* will be clamped between the levers *p* and *S*, and will consequently be prevented from revolving. The annular rail *G* can be made of wood, covered with iron, or of any other suitable material.

Having thus described my invention, I claim as new, and desire to secure by Letters Patent—

1. The device for connecting the crank *b* of the axle *B* with the cranks *h h* on the spindle of a windmill, said device consisting of the jointed bifurcated rod *J* and annular plate *m*, in combination with the jointed rods *J' n*, and plate *o*, all made and operating substantially as described.

2. The jointed swivel-rod *I*, connecting the axle *B* with the spindle of a windmill, in combination with the jointed rod *J*, annular plate *m*, plate *o*, and jointed rods *J' n*, all made and operating substantially as herein shown and described.

J. TOBIAS BRAUN.
